UNITED STATES PATENT OFFICE.

C. PYLE WIGGINS, A. H. NORDYKE, AND B. STRAWBRIDGE, OF RICHMOND, INDIANA.

MACHINE FOR FOLDING PAPER.

Specification of Letters Patent No. 18,075, dated August 25, 1857.

To all whom it may concern:

Be it known that we, C. PYLE WIGGINS, A. H. NORDYKE, and BENJAMIN STRAWBRIDGE, all of the city of Richmond, in the county of Wayne and State of Indiana, have invented certain new and useful Improvements in Machines for Paper Folding; and we do hereby declare that the following is a full, clear, and exact description of the construction and operation of the same, reference being had to the annexed drawings, making a part of this specification, in which—

Figure 1, is a perspective view of our invention. Fig. 2 shows the contrivance which prevents retraction of the paper.

A, A, A, constitute a rectangular framework, as shown, permanently framed together in a suitable manner, and upon which is secured the metallic frame B, B, B; in the upper plate of this frame is a long slot or opening, b, which is an entrance to a sort of throat composed of upright bars, b', b', b', standing in double ranks.

b'', b'', Fig. 2, represent part of another set of bars and another throat, at right angles with b', b', b'.

C, is a folding blade directed in its motion by guides in part E, (not shown). Blade, C, is operated by cords, c, c'. It folds a sheet of paper in the middle when properly laid upon plate, B.

D, is also a folding blade which receives and folds the paper after it has been folded by blade, C. It is operated by cords, d, d'.

The folding may be multiplied to any required number of times without any addition of machinery save an additional number of blades, pulleys and drums, the drums 40 being placed upon the same shafts with those already shown.

F, is a flanged drum upon shaft, f. Upon one part of its periphery is coiled a portion of the cord, c, on the other part, a corresponding portion of cord c'; but in an opposite direction, so that as one is coiled the other is uncoiled and vice versa.

G is a drum similar to F, with also an arrangement of cords, d, d', similar to 50 cords, c, c'.

f', g', are pinions upon the outer ends of shafts f and g, respectively.

H, is a lever swung in an adjustable fulcrum or pivot frame i. At its lower ex-

tremity is a toothed segment which actuates 55 pinion, f. Its upper end passes behind cam wheel L, and is armed with a stud l.

H', is a lever similar to H. It has also an adjustable fulcrum, j.

i, is an adjustable fulcrum to lever H. It 60 receives lever, H, in a mortise through its body as shown, and retains it in position by means of a set screw. Upon its back is a small boss or stud which passes loosely through plate K so as to allow free lateral 65 vibration of, i, but it is headed to prevent retraction.

j, is a device similar to i.

K, is a plate which receives studs from fulcrums i, j. It is adjustable by means of 70 set screws at each end, as shown, in combination with fulcrums, i, j. It affords a ready means of changing the position of the center of motion of lever, H H, thereby regulating the stroke of the blades, C, D, according to the size of the paper to be folded. 75

The dotted lines, m show the shape of the flanges or cam upon wheel, L, which actuates levers, H, H'. This cam is half eccentric and half concentric so that while 80 one of the levers is in motion, the other is at rest.

Wheel, L, is borne upon a short shaft which has boxings upon the framework of the machine.

M, is a winch by which the machine is operated.

N, O, P, constitute a device by means of which the paper is prevented from retraction with the blade after it has received a 90 fold.

N, is a sort of movable jaw pivoted near its middle as shown and held in position by a small spring.

O is a fixed jaw against which, N, may be 95 made to grip the paper.

P is a lever with its center of motion upon bracket, p. One end of this lever is in contact with jaw, N, the other presents an inclined surface across the path of blade 100 D. Bracket, p, is placed diagonally upon bars b'' b''; its shape is sufficiently indicated in the figure. As blade D enters the sort of throat in which the paper is folded it comes in contact with lever P, pressing 105 it outward thereby causing, N, to clamp the paper against O, and prevent its retraction.

Operation: Continuous rotation should be

communicated to wheel L by means of the handle M. This causes an alternate action of the blades C, D. As already shown, when the blade C, has arisen from the slot, 5 b, and is at rest awaiting the action of blade D. A sheet to be folded, is laid properly upon the plate B. Blade C, now descends upon the paper forcing it into the throat formed by uprights, b, b', and folding it 10 evenly and smoothly its entire length. Blade, C, is now retracted, and while blade D is performing its work. Another sheet is laid upon plate B, blade C, again descends. And thus on continuously till the 15 desired number is folded.

This machine is by no means complex in construction is not liable to wear or fracture, is easily adjusted to any requisite size of paper, and performs its work well. It 20 may be connected to a cylinder press and receive the papers directly from the fly thus

entirely dispensing with the labor of laying on by hand.

Now what we claim as new and useful and desire to secure by Letters Patent is— 25

1. The combination of cam wheel, L, with lever H', pinion g' shaft g drum, G, cords, c, c', and blade, C, for purposes shown.

2. The combination of cam wheel, L, with levers, H, H', pinions, f', g', shafts f, g, 30 and drums, F, G, for the purpose of producing an alternate movement of blades, C, D, as set forth.

3. The combination of jaws or clamps, N, O, and lever P, with blade, D, to prevent 35 retraction of the paper.

C. PYLE WIGGINS.

A. H. NORDYKE.

B. STRAWBRIDGE.
